SMOKING APPLIANCE

Galen M. Pierson, El Paso, Tex.

Application October 27, 1938, Serial No. 237,315

5 Claims. (Cl. 131—209)

This invention relates to an improved smoking appliance constructed to provide means for cooling and cleaning the smoke passing therethrough.

It is an aim of this invention to provide an improved attachment for use with cigar and cigarette holders or pipes which will form a trap to catch the nicotine carried by the smoke and which will direct the smoke by an indirect route to permit it to be cooled before reaching the mouth of the smoker.

More particularly, it is an aim of this invention to provide an improved construction of stem for pipes or cigar and cigarette holders provided with a chamber adapted to contain a removable insert, which diverts the smoke passing therethrough by a plurality of indirect channels for cooling the smoke and for entrapping the nicotine; said insert being readily removable and so constructed that it may be easily cleaned.

Still a further aim of the invention, is to provide a stem for smoking appliances in which an improved trap may be removably mounted, said trap being constructed to connect the opposite ends of the stem to thereby form a chamber in which it is removably contained.

Other objects and advantages of the invention will hereinafter become more fully apparent from the following description of the drawing, which illustrates a preferred embodiment thereof, and wherein:

Figure 1 is a side elevational view showing the invention embodied in a smoking pipe.

Figure 2 is an enlarged side elevational view partly in section, of the same embodiment, showing the means for removably mounting the insert.

Figure 3 is a plan view of one side or face of the insert.

Figure 4 is a sectional view taken along the line 4—4 of Figure 3.

Figure 5 is a plan view of the inner side of the removable socket member, and

Figure 6 is a sectional view taken along the line 6—6 of Figure 5.

Referring more particularly to the drawing, wherein like reference characters designate like or corresponding parts throughout the different views, 10 designates generally a smoking pipe, which has been illustrated in Figures 1 and 2, constructed in accordance with the present invention. However, it is to be understood that the invention, which will hereinafter be described, may be equally well adapted to cigar and cigarette holders, as will hereinafter be explained.

Pipe 10 is provided with a bowl 11, of conventional construction, having an internally

threaded outwardly projecting socket portion 12 formed integral with a portion of the lower part thereof and provided with a passage 13 extending through the lower part of the bowl 11 and centrally through the socket portion 12.

A stem 14 having a longitudinal passage 15 is provided with a bit 16 at one end, of any suitable construction, and is internally threaded at its opposite end to receive the externally threaded tit 17 of the socket member 18 which 10 is provided with the internally threaded portion 19 corresponding with portion 20 of socket 12. It will thus be seen that the socket member 18 is removably mounted in the stem 14 by means of its threaded tit 17, and as seen in Figure 2, 15 is provided with a bore 21 which extends centrally through the socket member 18 and the tit 17 to communicate with bore 15.

A disk-shaped insert, designated generally 22, is provided with a threaded periphery 23 adapted 20 to engage the internally threaded flanges 19 and 20 of the socket members 18 and 12, respectively, as seen in Figure 2, to connect these parts to thereby form the chamber 24 in which the insert 22 is adapted to be removably mounted. As seen 25 in Figure 2, the periphery of the socket members 12 and 18 are of the same size and the flanges 19 and 20 are the same thickness and length so that when assembled on the insert 22 the two socket members fit flush against each 30 other to provide a smooth outer surface. Furthermore, the thickness of the chamber 24 formed by the socket members is substantially equal to the thickness of the insert 22 so that its opposite sides rest flush against the inner sides of 35 the socket members 12 and 18.

One side of the insert 22 is provided with a recess 25 which communicates with the transverse passages 26 which are disposed in opposed relationship to each other and adjacent the periphery 23, as seen in Figures 3 and 4. The opposite side of the insert 22 is provided with the spiral grooves 27 and 28. The corresponding 40 ends of each of these grooves connect with the concave centrally disposed recess 29 in the center 45 of this last mentioned side, while the opposite ends of the grooves 27 and 28 each connect with an end of a passage 26 to combine with the recess 25 for forming two continuous conduits from the center of one side of the insert 22 to 50 the center of the opposite side.

As seen in Figure 2, insert 22 is mounted in chamber 24 with the recess 25 facing toward the socket 12 and communicating with the passage 13, while the opposite side of the insert lies flush 55

against the inner side of socket 18 which thereby converts the grooves 27 and 28 into spiral passages extending from passages 26 to the recess 29, which communicates with passage 21.

5 From the foregoing it will be seen, that smoke may pass from the bowl 11 through passage 13 to the recess 25 where it may divide and pass in opposite directions, radially outwardly, to the two transverse passages 26 which convey the smoke 10 to the opposite side of the insert 22 from whence it passes through the grooves or passages 27 and 28 to recess 29, thence through passage 21 through passage 15 and through the bit 16. It will thus be seen, that the insert 22 forms a 15 trap which collects the nicotine from the smoke passing therethrough and which carries the smoke by an indirect route giving it an opportunity to be cooled before entering passage 15. Obviously, insert 22, which is readily removable, can be 20 easily cleaned, since when removed the recess 25 and the grooves 27 and 28 are exposed and may easily be wiped clean of any nicotine collected therein and the passages 26 which are very short can likewise be easily cleaned before replacing 25 the insert.

Although the invention has been illustrated in connection with a smoking pipe it is obviously equally well adapted for cigar and cigarette holders in which form, the socket 12, instead of being 30 formed integral with the pipe bowl could be formed integral with the cigar or cigarette receiving end of a holder or could be removably connected thereto as the socket 18 is connected to the stem 14. The size of the sockets 12 and 18 35 and the insert 22 could each be correspondingly decreased when the invention is constructed in the form of a cigar or cigarette holder, and may likewise be decreased in size when constructed as a pipe, if desired, as the invention is not intended to be limited by the drawing and description 40 to any particular size or proportions of the various parts thereof.

Various other modifications and changes are 45 likewise contemplated and may obviously be resorted to without departing from the spirit of the invention, and the right is expressly reserved to make such variations and changes as fall within the spirit of the invention as hereinafter defined by the appended claims.

50 I claim as my invention:

1. A smoking appliance comprising a passage having an enlarged intermediate portion, a member mounted in said intermediate portion and provided with a concave side communicating with 55 the inlet end of said passage, said member being provided with a plurality of openings disposed adjacent its marginal edge, said openings communicating with said concave portion, and a plurality of spirally disposed passages on the opposite 60 side of said member connecting said openings and the outlet end of said first mentioned passage.

2. A smoking appliance provided with an enlarged portion in its stem, said enlarged portion

including separable internally threaded socket members, an insert having a threaded periphery for engagement with said socket members for forming the enlarged portion with the removable 5 insert contained therein, said insert fitting snugly within said enlarged portion and being provided with a concave face at one side communicating with the passage at one end of said stem, passages extending through said insert adjacent its periphery, and spiral grooves formed in the opposite side 10 of said insert and connecting said last mentioned passages and the passage in the opposite end of said stem.

3. A smoking appliance comprising a stem 15 formed of sections each provided with a longitudinal passage, the adjacent ends of said sections being provided with enlarged internally threaded socket portions, an insert having a threaded periphery to engage said socket portions to thereby 20 connect them to provide a chamber in said stem in which said insert is removably mounted, and said insert having bores extending therethrough, adjacent its periphery, channels in one side of the insert communicating with corresponding 25 ends of the bores and with one of said passages, and a channel in the opposite side of the insert 30 communicating with the opposite ends of the bores and with the other passage for connecting the passages of the opposite ends of said stem.

4. A smoking pipe comprising a bowl having an 35 internally threaded socket portion projecting therefrom, a passage connecting said bowl and socket portion, a stem having a socket portion in one end thereof, internally threaded, to correspond to said first mentioned socket portion, and an insert having a threaded periphery to be engaged by said socket portions to connect them to form a chamber for containing said insert, bores formed in and extending through said insert 40 adjacent its periphery, one side of said insert being channelled to communicate with corresponding ends of said bores and with said passage, spiral grooves formed in the opposite side 45 of said insert and having corresponding ends each communicating with the opposite end of one of said bores, said last mentioned socket portion combining with said grooves to form passages, and a longitudinal passage formed in said stem and communicating with the opposite ends of 50 said grooves for connecting said stem and pipe bowl.

5. An attachment for smoking pipes comprising a member having spaced passages extending therethrough, one side of said member having a channel portion communicating with corresponding ends of the passages, the opposite side of said member having grooves provided with adjacent connecting ends, the opposite ends of 55 said grooves communicating with the opposite ends of said passages, and means for detachably mounting said member in the stem of a smoking pipe.

GALEN M. PIERSON.
